UNITED STATES PATENT OFFICE.

JOHN DILL, OF NEW YORK, N. Y.

AEROPLANE.

Application filed May 29, 1926. Serial No. 112,481.

This invention relates to aeroplane construction and is directed to numerous features of novelty adapted to facilitate the handling or manipulation of a plane, both in the air and on the ground.

One of the important features of the invention is the provision of simple and efficient means whereby the angle of incidence of the wings may be altered and adjusted to suit particular conditions. Wholly novel and efficient means is provided for the performance of this important operation and the pilot is adapted to control this mechanism in a simple and efficient manner.

Another highly important feature of the invention consists in the provision of an aeroplane with adjustable incidence and the utilization of a propeller of adjustable pitch with means to vary the incidence of the wings and adjust the pitch of the propeller, these adjusting mechanisms being interconnected in such manner that when the incidence is changed, the pitch of the propeller will be simultaneously adjusted, so as to give the most efficient pitch for the new angle of incidence. In this manner, the efficiency of the plane throughout its varying adjustments of incidence is maintained at the highest point thereby rendering the operation of the plane, while in the air, as safe, as possible and serving further to obtain the highest efficiency for the power expended by the motor in the doing of useful work.

Another important feature of the invention resides in aeroplane construction so constituted that the wings of the plane may be folded by an occupant of the plane without leaving the fuselage or nacelle thereof. The apparatus whereby this folding of the wings is carried out is adapted to fold the wings inward toward the fuselage or to unfold the wings to position them in flying condition. The folding of the wings is important for commercial, military and naval aviation because of the less amount of space required for storing or housing.

In addition to the foregoing principal features to which I have referred, the invention embodies numerous supplemental features and advantages which will be apparent from the hereinafter detailed description and from the appended claims.

The accompanying drawings illustrate one practical embodiment of the invention, but the construction shown therein is to be under-

stood as illustrative, only, and not as defining the limits of the invention.

Figure 1 is a side elevation of an aeroplane embodying the present invention. The wings are illustrated in this figure in flying positions.

Figure 2 is a side elevation of the aeroplane with the starboard wings tilted preliminary to folding them into compacted positions and the port wings illustrated as folded into the latter positions.

Figure 3 is a front elevation of the aeroplane showing the starboard wings in folded compacted positions and the port wings in flying positions.

Figure 4 is also a front elevation with both the starboard and port wings in folded position.

Figure 5 is a plan view of the parts as shown in Figure 4.

Figure 6 is a section taken in substantially the plane of the line 6-6 of Figure 1, looking in a forward direction and illustrating fragments of the spars of the wing in section and the fuselage being shown with longérons in section and the covering of the fuselage removed.

Figure 7 is a fragmental side elevation of a portion of the fuselage adjacent the center.

Figure 8 is a section on the line 8-8 of Figure 6.

Figure 9 is a section on the line 9-9 of Figure 8.

Figure 10 is a diagrammatic assembly of the forward portion of the aeroplane in perspective.

Referring to the drawings, 1 designates the fuselage of the plane. It is constructed in any suitable manner with appropriate longérons 2 properly braced in any approved fashion. Its design and shape is not important in so far as the present invention is concerned and in practice, it may be of any appropriate stream-line configuration and may be built up structurally of longérons, rigid bracing and bracing wires or may be of a monocoque construction. Furthermore, while the invention has been shown in the accompanying drawings as associated with tractor aeroplanes, embodying a fuselage, it may be also utilized in aeroplanes of the pusher type in which event a suitable nacelle will be used in lieu of a fuselage.

An engine, not shown in the drawings, is mounted on the fuselage in the construction

shown and is equipped with a propeller 3 which, in practice, may be of any conventional rigid type, but in order to carry out all of the advantages of this invention it is 5 preferably of the adjustable type, of which several are well known to the art. Adjustable propellers are those wherein the blades are mounted for adjustment to vary the pitch or helix of the propeller. It has not been 10 considered necessary to illustrate such propeller in detail, but it may be here noted that the adjustment of the propeller is obtained by rotating a shaft 4 as shown best in Figures 7 and 10. This shaft extends rearwardly 15 from the propeller to the means for operating it, hereinafter more fully explained.

The aeroplane is provided with upper wings 5 and lower wings 6, with which are associated upper and lower center sections 20 7 and 8. It is of the essence of this invention that the wings be susceptible of change in incidence and, as shown in the drawings, the center sections are also adapted for a corresponding change. To permit of this operation, the upper center section is mounted for 25 pivotal movement on a bar 9 (see Figs. 5 and 7) and this bar is supported in fixed position on consoles 10, mounted on the upper longérons (Fig. 7). In a similar manner, the 30 lower center section 8 is pivotally mounted on a transverse bar 11 carried by brackets 12 secured to the lower longérons. The upper and lower center sections 7 and 8 are secured to one another by two upright operating 35 struts 14 and 14^a. These struts preferably connect the center sections at the rear spars thereof and adjacent both lateral edges of the center sections. They extend in substantially vertical position and, in the preferred 40 form of the invention, are constructed after the manner illustrated in Figures 8 and 9. From these figures, it will be noted that the adjusting struts are preferably of hollow sheet metal construction, bifurcated at their 45 opposite ends and pivotally connected by pivot pins 15 to lugs 16 mounted on the spars 17 of these center sections. The spars are shown as of hollow tubular form.

It will be apparent that with the two center 50 sections, pivoted as described, and connected together by adjusting struts in the manner specified, a vertical adjustment of these struts will effect a simultaneous variation of the incidence of both center sections. Various 55 mechanical means may be utilized for this purpose, and the construction shown in the drawings is typical rather than exclusive. In this showing (see Figs. 6 and 7), an upright threaded post 18 is mounted at each of 60 the lower longérons 2 and extends upwardly through a bracket 19 rigid with one of the struts 14, 14^a.

A nut 20 is rotatably carried by each bracket and integral with the nut is a bevel 65 gear 21. With each bevel gear meshes a

pinion 22 and these two pinions are fixed to the opposite ends of a shaft 23, extending transversely of the fuselage and carried by the adjusting struts. A hand wheel 24 is fixed to the shaft 23 and by means of this 70 hand wheel, which is within ready access of the pilot, the shaft may be rotated to rotate the nuts 20. The posts 18 are provided with right and left hand threads, respectively, so that when the nuts are rotated, the struts 14, 14^a are caused to be vertically adjusted in 75 one direction or the other depending upon the direction of rotation of the hand wheel. By this operation, the rear spars of both center sections are simultaneously raised or 80 lowered, while the front spars of such sections remain relatively stationary, so that by this operation, the incidence of both center sections is simultaneously varied.

It will be noted from Figures 6 and 10 that 85 there is associated with the shaft 23 an additional pinion 25 which meshes with the gear 26 carried on the shaft 4. Inasmuch as the shaft 4 controls the pitch of the propeller, it follows that the variation of incidence of 90 the center sections simultaneously brings about a change in propeller pitch. In practice, the parts are so associated and the gearing is of such a ratio that changes of propeller pitch will be appropriate to changes in 95 incidence in order that the proper relationship between these important features may be preserved in order to give maximum efficiency during flight.

In carrying out this invention in its preferred form, the wings 5 and 6 are mounted on the respective center sections for change of incidence therewith and the mounting is also adapted to permit of a bodily folding operation of the starboard and port planes into 100 compact position, substantially parallel to the fuselage to facilitate storage. To permit of this, the forward spars of each of the upper and lower wings are pivotally secured to 105 opposite ends of the bars 9 and 11 (Figs. 5 and 7) in such manner as to permit universal movement of the wings. Thus, in Figure 5, the spars 27 of the upper planes are shown as secured, by means of pivots 28, to the opposite 110 ends of the bar 9, so that the said spars may be swung into and out of alignment with said bar, while the mounting of the bar is such as to permit rocking thereof. This will provide for the universal movement referred to. The spars of the lower planes are similarly 115 associated with the bar 11.

To provide for the several movements of the planes as referred to, it is further essential to provide for a detachable connection between the rear spars of the respective planes and the corresponding spars of the center sections. The manner in which this is accomplished is clearly shown in Figure 6. Here both upper and lower center sections are 120 shown as provided with attaching bolts 29 po- 125 130

sitioned in alinement with the respective rear spars of the upper and lower planes, and said spars are provided with threaded pockets 30 to receive these screws. The screws are 5 mounted in the center sections for longitudinal movement and are suitably guided for this operation. Each screw is squared for a portion of its length, as shown at 31, and associated with each squared portion is a sprocket 10 32 precluded from edgewise movement by means of stops 33. Extending vertically through the associated adjusting struts 14, 14^a are endless sprocket chains 34 shown best in Figure 8. These chains encircle the superimposed sprockets 32 of the upper and lower center sections and within the struts are positioned adjusting sprockets 35.

A shaft 36 extends transversely of the struts 14, 14^a and is mounted to rotate therein 20 and on this shaft the pinions 35 are fixed. A hand wheel 37 carried by one end of the shaft permits of the operation of both sprockets 35 simultaneously and as a result both sprocket chains are operated to simultaneously rotate 25 all of the bolts 29 to cause them to be projected into threaded engagement with the sprockets 30 of the spars or to be retracted from said pockets, depending upon the direction of rotation of the hand wheel 37.

30 It therefore follows that if the upper and lower wings are brought into flying position, all of the screws 29 may be simultaneously advanced to secure the rear spars of all of the wings to the center sections. When it is desired to subsequently release the wings for a folding operation, all of said screws may be simultaneously retracted to permit of such operation.

The wings are spaced apart with outboard 40 struts, the forward struts being designated 38 and the rear struts 39. The forward struts are rigid and this structure is best shown in Figure 10, wherein they are shown as having pivotal connection at their upper and lower 45 ends with the respective wings and further as off set rearwardly at their opposite ends to provide for pivotal movement of the wings as hereinafter more fully described. Anti-friction bearings 40 preferably cooperate with 50 the pivotal connection between the struts 38 and the wings in order that pivotal movement of the wings with respect to the struts may be rendered as free from friction as possible. The rear struts 39 are jointed midway of their 55 length as shown at 41, so that each of these struts constitutes in effect a toggle. The pivot at the elbow of the toggle is off center of the line of thrust imposed by the wings when the sections of the toggle are in alinement and 60 in this way inadvertent collapsing of these struts is precluded.

65 Springs 42 (Figs. 4 and 10) are also associated with the elbows of the toggles and normally tend to force the links thereof into alinement. The opposite ends of the toggle

sections or links are pivotally connected to the upper and lower planes, as shown in Figure 10, to permit of flexing of the toggles.

It is conventional in biplane construction to provide interplane bracing known to the 70 art as the landing wires, the flying wires, incidence wires, etc.

In the construction shown in the drawings, landing and flying wires of the conventional form may be associated with the planes adjacent the forward spars, these wires being secured to the struts 38, the fuselage and consoles 10. Inasmuch as this will be readily understood by those skilled in the art, I have not considered it necessary to show these 80 wires in the drawings, but have limited the drawings, particularly with regard to Figure 10, to a showing of a novel form of wiring whereby the wings are supported in such manner as to permit a change of incidence 85 and also allow of the wings to be tilted and folded into and out of compacted position with reference to the fuselage. This novel wiring will now be described in detail.

Referring to Figure 10, attention is first 90 directed to the wire 43. It is secured at one of its ends at the elbow of the toggle and is led over directional pullers 44 to a drum 45 loosely mounted for rotation on the shaft 23 (Fig. 6) and with this drum is rigidly associated a hand wheel 46 whereby the wire 43 may be coiled upon the drum or unwound therefrom. Suitable means (not shown) for locking the drum against unwinding is preferably provided. The purpose of this wire 95 43 is to collapse the rear strut 39 when desired and, in practice, one of these wires is associated with the port, as well as with the starboard wings.

In describing additional wires, I will specify only those associated with the starboard wings, it being understood that they are duplicated for the port wings.

The wire 47 is attached at one end to the inboard end of the rear spar of the upper 100 wing, whence it extends in a downward diagonal direction and passes through a directional pulley positioned near the lower end of the rear strut 39 as shown at 48. This stretch of the wire functions as the rear landing wire. From the pulley 48, the wire extends in an upward diagonal direction through a pulley at the upper end of the forward strut 38, this portion of the wire serving as an incidence wire. Thence the wire 115 extends to a directional pulley 49 and about other directional pulleys 50 to a drum 51 carried by the adjusting strut 14^a.

The drum 51 is mounted on a shaft 52 carried by the strut 14^a, as shown in Figures 6 125 and 7 and said shaft also carries a second drum 53 at its opposite end. Intermediate its ends, the shaft is provided with a worm wheel 54 which meshes with the worm 55. The worm is carried on a transverse shaft 56 130

- having bearings in the struts 14 and 14^a and at one end of said shaft is fixed a sprocket 57 having a chain connection 58 with a second sprocket 59 mounted on a stub shaft 60.
- 5 Fixed with respect to the pulley 59 on the stub shaft 60 is a hand wheel 61 by means of which the drum may be operated to control the tension of the wire 47 throughout its entire length and to thereby provide for pres-
- 10 sure means of adjusting the incidence of the wings on the starboard side of the plane.

Coiled about the other drum 53, to which I have referred, is a wire 62. This wire leads about suitable directional rolls to the lower 15 end of the forward strut 38 whence it extends upwardly in a diagonal direction to the upper end of the rear strut 39, constituting for this stretch of the wire a second incidence wire. At the upper end of the strut 39, the wire 62 20 passes through a suitable pulley and is then led diagonally downward in an inboard direction to the inboard end of the rear spar of the lower plane where it is secured. That portion of the wire between the pulley 43 25 and its point of attachment last described performs the function of a flying wire.

It is to be noted that the wires 62 and 47 are coiled upon the drums 51 and 53 in opposite directions, i. e., one right hand and the 30 other left hand, so that when these drums are simultaneously operated by the hand wheel 61, one wire will be wound while the other is unwound. The reason for this arrangement will be presently described.

35 The wire 64 is secured at one end to the upper end of the strut 38 and is led downwardly and forwardly to a bracket 65 which stands out from the side of the fuselage and is preferably stream-line or in the shape of an aerofoil as shown. Passing through the 40 bracket 65 by means of suitable directional pulleys, the wire 64 is led rearwardly within the fuselage and is coiled about a drum 66, mounted on the shaft 67 which is operatively connected by means of a chain and sprocket 45 connection to a hand wheel 68. Also mounted on the shaft 67 is a second drum 69 about which is coiled a wire 70 which extends over directional pulleys and is secured at its distant 50 end to the upper side of the upper wing at its forward spar at 71.

The wires 64 and 70 are coiled about the drums 69 and 66 in opposite directions, so that when one is unwound, the other is wound. It may be here noted that that portion of each wire 64 which extends from the bracket 65 back to the point where it is secured to the upper end of the outboard strut 38 serves the function of a drag or drift wire. 55 I have for convenience of description referred to the supports just described as "wires", but it will be understood that in practice they may be either of wire, cable or wire rope.

In practice, all of the hand wheels or other 60 operating devices whereby these wires or

cables are operated are preferably positioned within easy access of the pilot's seat which is designated in the drawings by the reference character 72 located in the cock pit 73. Thus when the pilot is occupying the seat 72, 70 all of the operating devices referred to are within easy access, so that he may at will perform the practical operations next to be described.

If it is assumed that the aeroplane is in a 75 hangar, the parts will be in the positions shown in Figures 4 and 5, wherein it will be noted that the wings are folded into compact form. The motor may be started and the ship "taxied" out of the hangar under its own power. When the ship has been brought into the open, the wings should be moved into flying positions. This is accomplished by first operating the hand wheel 68 to wind the cable 64 upon the drum 66 and to simultaneously unwind the cable 70 from the drum 69. By this operation, the cable 64 will cause the wings to be swung outwardly on their universal joints until the spars of said wings are in alinement with the spars of the center sections. As the cable 64 is wound to draw the wings outwardly, the wire cable 70 will be unwound to permit of this movement of the wings.

80 After the wings have been extended, as described, the hand wheel 46 is operated to place the cable 43 under tension and to wind the cable upon the drum 45. As the cable is wound up, it will serve to straighten out the toggles which constitute the rear struts 39 of both wings. The manner in which this operation takes place will be apparent from Figure 2, and obviously the operation of drawing the sections of these struts into alinement will tilt the bottom wings into substantially horizontal position and simultaneously tilt the top wings into substantially horizontal position. After the cables 43 have been drawn sufficiently to effect an appreciable straightening of the sections of the rear 105 struts, the springs 42 will tend to finish this operation.

110 After the wings have been brought into substantially flying position, the hand wheel 37 is operated to advance the wing attaching screws 29 by which operation the rear spars of the several wings are secured to the respective center sections.

The operation of straightening the rear struts and the forcing of the wings into substantially flying position will manifestly bring about a tensioning of the cables 47 and 62, but after this operation is complete, slight manipulation of the hand wheel 46 may be desirable to bring the parts into accurate flying positions. The wings are brought into flying position in the manner which I have described and it will be apparent that the angle of incidence of the wings and center sections may be changed at the will of 125 130

the operator by merely manipulating the hand wheel 24 to raise or lower the adjusting struts. This operation varies the incidence of the center sections and the wings which are mounted thereon will partake of a like variation.

The automatic variation of incidence of the wings to correspond with variations in incidence of the center sections, necessarily follows from the fact that as shown in Figure 10, the free end of the wire 47 is secured to the rear end of the upper center section, while the free end of the wire 62 is secured to the rear end of the lower center section. Thus, if the incidence of the center sections is decreased, there will be a slight slackening of the wire 62 and a corresponding tightening of the wire 47 with the result that the incidence wires between the outboard struts will be correspondingly lengthened and shortened to produce a change in incidence corresponding to the change of incidence which has occurred in center sections.

In order that the pilot may know the incidence at which the planes are set, I preferably provide an indicator shown in Figure 6. This indicator embodies a suitable graduated scale 100 with which cooperates an indicating finger 101. A spring 102 impels the indicating finger in one direction, while opposed to the spring is a wire 103 which extends over a directional pulley 104 and is secured to the adjusting strut 14. As this strut is elevated to decrease the incidence, the spring is permitted to move the indicating finger in one direction and when the strut is lowered, the wire 103 will draw the indicating finger in the other direction. The graduated scale may be marked in degrees, so that by knowing the position of the indicating finger the pilot may see at a glance the degree of incidence at which the planes are set.

All of the operations which have been described may be carried out by an occupant of the cockpit. In other words, the parts may be brought into accurate flying positions by the pilot without leaving the cockpit. This feature of the present invention is distinctly novel in aviation.

I have described the manner in which the wings are moved from compacted positions into flying position and it will be understood that the wings may be moved from flying position into compacted position by a reversal of the operations described. It thus appears that after making a landing, the pilot may move the wings into compacted positions and taxi into the hangar without leaving the seat of the ship. The importance of this phase of the invention will be obvious to those skilled in the art. It not only permits of one man control and operation of the ship, but greatly facilitates the storing of an aeroplane. It is of obvious importance from commercial, mil-

itary and naval aviation standards because of the lesser housing space and because of convenience in transportation without necessitating dismantling. Furthermore, the ability to compact the plane in the manner described renders it more easily camouflaged from an enemy when on the ground.

It will of course be understood that the aeroplane is provided with a suitable undercarriage and appropriate empennage, tail skid and other adjuncts well known to the art, and that the flying controls may be of any conventional type. I wish to lay particular stress upon the ability of the pilot to change incidence while in flight and also to the automatic manner in which the pitch of the propeller is simultaneously adjusted to compensate for variations in incidence.

In the preferred form of the invention, these adjustments are simultaneously made and are interconnected, so that the adjustment of incidence will correspond with the adjustment of propeller pitch. By this arrangement, maximum flying efficiency is obtained and preserved. I am aware, however, that certain advantages of the invention may be obtained without necessarily changing the propeller pitch and accordingly while the simultaneous adjustment is preferred, the invention in its broad aspect is not limited in this connection.

For the reasons given, the invention is not restricted to the specific construction shown or to the particular combination described. Some of the features of the invention may be employed without necessarily employing all and structural details may be varied as will be apparent to those skilled in the art without departing from the invention, the scope of which is to be understood as fully commensurate with the appended claims.

Attention may be directed to the fact that the axes on which the wings are pivotally moved to adjust the incidence pass through approximately the center of lift of each wing. If the plane has any dihedral, the axis of one wing will be a continuation of the other and will correspond to the axis of the center section, but if there is a dihedral angle, the axes will of course be different for both wings and center sections.

The advantage of having these axes extend approximately through the centers of lift will render the tilting of the planes to vary the incidence relatively easy, so that little power will be required to effect a change in incidence.

Attention may be also called to the fact that in the moving of the wings from flying to compacted positions, and vice versa, no separate adjuncts or attachments are required. I am aware of the folding construction common to such aeroplanes as the Handley Page. It will be apparent, however, that the system of folding the wings of planes

such character is totally distinct and different from the system of the present invention and requires the use of false struts and other adjuncts for carrying out the folding operation which must, moreover, be accomplished by a large number of men working outside of the fuselage or nacelle.

I have hereinbefore specifically directed attention to the apparatus of this invention. I am aware, however, that the invention also embodies novel methods of manipulating the parts of a flying machine and these methods are to be understood as also forming part of his invention.

Having thus fully described the invention, what I claim as new and desire to secure by Letters Patent is:

1. A flying machine embodying port and starboard wings capable of adjustment to vary the incidence thereof, a propeller capable of adjustment to vary the pitch thereof, and interconnected means for simultaneously varying the incidence of the wings and the pitch of the propeller.

2. A flying machine embodying port and starboard wings mounted for bodily pivotal movement to vary the incidence of the wings, means for pivotally adjusting said wings to the desired incidence, a propeller capable of adjustment to vary the pitch thereof, and means interconnected with the wing adjusting means for varying the pitch of the propeller.

3. A flying machine embodying port and starboard wings capable of adjustment to vary the incidence thereof, a propeller capable of adjustment to vary the pitch thereof, mechanism for varying the incidence of the wings, mechanism for varying the pitch of the propeller, and common operating means for both of said mechanisms, whereby proper flying relation is maintained between incidence and pitch.

4. A flying machine embodying a center section pivoted on a substantially horizontal transverse axis, port and starboard wings secured to the center section and pivotally movable therewith on transverse axes extending approximately through the centers of lift of said wings, means, operable from within the machine to adjust the outer end portions of the wings to the desired incidence with respect to the incidence of the center section, and means for thereafter simultaneously correspondingly varying the incidence of both the wings and center section.

5. A flying machine embodying a center section pivoted on a substantially horizontal transverse axis, port and starboard wings secured to the center section and pivotally movable therewith on transverse axes extending approximately through the centers of lift of said wings, means, operable from within the machine to adjust the outer end portions of the wings to the desired incidence with respect

to the incidence of the center section, and means for thereafter simultaneously correspondingly varying the incidence of both the wings and center section, while maintaining the transverse relation (dihedral, if any) between the wings and center section.

6. A flying machine embodying upper and lower port and starboard planes spaced apart intermediate their ends by struts, incidence wires between the upper and lower planes at the struts, and means operable from within the machine for varying the length of the incidence wires.

7. A flying machine embodying a suitable fuselage or nacelle, upper and lower port and starboard wings extending laterally from the nacelle, struts positioned between the upper and lower wings for spacing them apart, incidence wires extending diagonally between the struts of the respective wings, and means positioned within the nacelle or fuselage and operable by the pilot for simultaneously varying the length of the incidence wires of the port and starboard planes to vary the incidence of such planes adjacent the struts.

8. A flying machine embodying a suitable fuselage or nacelle, upper and lower port and starboard wings extending laterally from the fuselage or nacelle, said wings being mounted for pivotal movement with respect to the fuselage or nacelle, struts positioned between the upper and lower wings at each side of the machine, incidence wires extending diagonally between the struts and adjustable from within the nacelle or fuselage to vary the incidence of the wings adjacent the struts, and means also operable from within the nacelle or fuselage for varying the incidence of the wings adjacent the fuselage or nacelle.

9. A biplane embodying port and starboard upper and lower wings capable of adjustment to vary the incidence thereof, a propeller capable of adjustment to vary the pitch thereof, and interconnected means for simultaneously varying the incidence of all the planes and the pitch of the propeller.

10. A biplane embodying upper and lower center sections mounted for pivotal movement, upper and lower port and starboard wings secured at their inboard ends to said center sections, struts for spacing the upper and lower wings apart intermediate the ends of said wings, incidence wires extending diagonally between the upper and lower wings adjacent the struts, means for pivotally moving the center sections simultaneously to vary the incidence of the center sections and the incidence of those portions of the wings adjacent the center sections, and means for simultaneously varying the length of the incidence wires to effect a corresponding change in incidence of the wings adjacent the struts.

11. A biplane embodying upper and lower center sections mounted for pivotal movement, upper and lower port and starboard

- wings secured at their inboard ends to said center sections, struts for spacing the upper and lower wings apart intermediate the ends of said wings, incidence wires extending diagonally between the upper and lower wings adjacent the struts, means for pivotally moving the center sections simultaneously to vary the incidence of the center sections and the incidence of those portions of the wings adjacent 5 the center sections, and means, automatically operable by a change of incidence of the center sections for simultaneously varying the length of the incidence wires to effect a corresponding change in incidence of the 10 wings adjacent the struts.
12. In a flying machine, upper and lower starboard and port planes mounted on relatively fixed pivots for pivotal movement adjacent their leading edges and said pivots being spaced apart a fixed distance, means for spacing the trailing edges of said upper and lower wings a substantially fixed distance apart, means for pivotally moving said wings to vary the incidence of the inboard ends of 15 the wings simultaneously, struts positioned between the upper and lower wings intermediate their ends, incidence wires extending diagonally between the wings adjacent the struts, and means for varying the length of the incidence wires to vary the incidence of the wings adjacent said struts.
13. A flying machine embodying a fuselage or nacelle, port and starboard wings mounted for pivotal movement on pivots fixed relative to the fuselage, adjusting struts spacing the inboard ends of the upper and lower wings vertically apart, complementarily threaded members carried by said struts and the fuselage and adapted, when operated, to vertically move the struts to vary the incidence of the wings at their inboard ends, a propeller capable of adjustment to vary the pitch thereof, mechanism for adjusting the propeller, and a single hand wheel operatively connected to the propeller adjusting mechanism and to the adjusting means of the struts, whereby the operation of the hand wheel will simultaneously vary the incidence of the planes and the pitch of 40 the propeller.
14. A flying machine embodying port and starboard upper and lower wings mounted for pivotal movement adjacent their leading edges on pivots spaced a substantially fixed 45 distance apart, struts for spacing the inboard ends of said wings a substantially fixed distance apart adjacent their trailing edges, a propeller capable of adjustment to vary the pitch thereof, and unitary means for adjusting the propeller to change the pitch thereof and for simultaneously vertically shifting said struts to vary the incidence of the wings.
15. A flying machine embodying port and starboard upper and lower wings mounted 50
- for pivotal movement adjacent their leading edges on pivots spaced a substantially fixed distance apart, struts for spacing the inboard ends of said wings a substantially fixed distance apart adjacent their trailing edges, a propeller capable of adjustment to vary the pitch thereof, and unitary means for adjusting the propeller to change the pitch thereof and for simultaneously vertically shifting said struts to vary the incidence of the wings, at the inboard ends thereof, and means automatically operable upon the change of incidence of the planes at the inboard ends thereof to effect a simultaneous like change of incidence of the wings 55 adjacent the outboard ends thereof.
16. A flying machine embodying upper and lower starboard and port wings spaced apart by suitable struts and braced by wires of which one incidence wire at each side of the machine is a continuation of a flying wire and the corresponding incidence wire at each side of the machine is a continuation of a landing wire.
17. In a flying machine, starboard and port planes pivoted for universal movement with respect to the fuselage or nacelle of the machine and extending in a lateral direction when in flying position, means for detachably securing the wings in flying position, 60 means for pivotally moving the wings on said universal joints, while in flying condition to vary the incidence thereof, said wings being adapted to be bodily swung upon the universal joints out of transverse flying position 65 into compacted position in which they extend fore and aft of the machine.
18. In a flying machine, port and starboard wings pivoted on universal joints, means for detachably securing the wings in transversely 70 extending substantially horizontal flying positions, means for varying the incidence of the wings while in flight, means for tilting the wings while in transverse position to bring their cords substantially upright, and means 75 for thereafter bodily swinging the wings into a position wherein they will extend fore and aft of the machine.
19. A flying machine embodying port and starboard wings pivoted for tilting movement upon horizontal axes and for swinging movement upon vertical axes, means for holding the wings in transversely extending flying positions, means for varying the incidence of the wings while in flight, said wings being 80 adapted, when released by the holding means, to be tilted on their horizontal axes into substantially upright positions, and thereafter swung on their vertical axes into compacted 85 position wherein they extend fore and aft of the machine.
20. A flying machine embodying port and starboard wings pivoted for tilting movement upon horizontal axes and for swinging movement upon vertical axes, means for hold- 90

ing the wings in transversely extending flying positions, means for varying the incidence of the wings while in flight, said wings being adapted, when released by the holding means, 5 to be tilted on their horizontal axes into substantially upright positions, and thereafter swung on their vertical axes into compacted position wherein they extend fore and aft of the machine, and means operable by the pilot 10 from within the machine for operating the holding means and moving the wings from their flying to compacted positions and vice versa.

21. A biplane having front and rear inter-plane struts between the upper and lower wings and the opposite ends of which struts are pivotally connected to the respective wings, the forward struts being rigid and the rear struts being of toggle form whereby 20 when the toggles are flexed the wings are tilted to bring their cords into substantially upright position.

22. In a biplane, upper and lower main planes, interplane struts for spacing said 25 planes apart, flying wires, landing wires and incidence wires between said planes, said incidence wires being continuations of the flying and landing wires.

23. In a biplane, a nacelle or fuselage, upper and lower main planes, mounted on the 30 nacelle or fuselage, interplane struts for spacing said planes apart, flying wires, landing wires and incidence wires extending between the upper and lower planes, said incidence wires being continuations of the flying 35

and landing wires, and means within the fuselage or nacelle for regulating the tension of said wires.

24. In a biplane, a nacelle or fuselage, upper and lower main planes mounted on the 40 nacelle or fuselage, interplane struts for spacing said planes apart, wire tensioning means within the fuselage or nacelle, wires extending from the wire tensioning means to the respective struts and constituting landing and 45 flying wires, and from thence extending in a fore and aft direction diagonally between the struts and constituting incidence wires.

25. A flying machine embodying a fuselage or nacelle, port and starboard wings mounted 50 for pivotal movement on pivots supported from the fuselage, incidence adjusting struts secured to the wings, and complementary threaded members operatively connected to the struts and to the fuselage and adapted, 55 when operated, to longitudinally move the struts to vary the incidence of the wings, in combination with a propeller capable of adjustment to vary the pitch thereof, mechanism for adjusting the propeller, and unitary 60 means operatively connected to both the propeller adjusting mechanism and to the threaded members and adapted when operated to simultaneously adjust the propeller and vary the incidence of the wings. 65

In testimony whereof, JOHN DILL has signed his name to this specification, this 24th day of May 1926.

JOHN DILL.
